UNITED STATES PATENT OFFICE.

JAMES P. EVERETTS, OF SAYRE, PENNSYLVANIA.

VACUUM STICKER OR ATTACHING DEVICE.

1,065,307.

Specification of Letters Patent. Patented June 17, 1913.

Application filed February 2, 1912. Serial No. 675,097.

To all whom it may concern:

Be it known that I, JAMES P. EVERETTS, a citizen of the United States, residing at Sayre, in the county of Bradford and State of Pennsylvania, have invented certain new and useful Improvements in Vacuum Stickers or Attaching Devices, of which the following is a specification, reference being had therein to the accompanying drawing.

10 This invention relates to vacuum stickers or attaching devices of a character adapted to connect parts or members, and is designed more especially for use in connection with the display of articles, in windows, show cases, etc.

One of the primary objects of the invention is to provide a sticker, exceedingly simple in construction, inexpensive, and at the same time one that will be durable in use 20 and efficient in operation.

It is the custom in stores to place in show cases and windows various advertising posters, placards, etc., and various forms of means have been provided for securing said 25 posters, etc., to the window pane, the more accustomed method being to provide paper strips or the like having an adhesive applied thereto adapted to paste the poster to the pane and it is contemplated by myself to 30 overcome objections incident to such attaching means and others which are at present in use, and to this end the invention includes a substantially integral structure which may be made relatively small, and one pleasing 35 in appearance whereby it does not detract from the otherwise neat appearance of the articles on display.

More particularly the invention includes a single piece rubber structure having a 40 body portion connecting at opposite ends with a cup shaped member, which said cup shaped members are adapted to be compressed due to the yieldability of the rubber and on pressure being relieved to create a 45 vacuum whereby they are held in place.

While the invention is more particularly designed for use in attaching posters and cards to the pane of a show window or the like, at the same time the device is of such 50 a character that it may be used to support other articles, and to this end the cup shaped terminals of the device when in use are preferably separated by an intervening unobstructed space whereby said cup shaped terminals 55 may project over the edges of the article to be supported and both of said cup

shaped members be engaged with the pane, in a manner to be more particularly referred to.

Other improvements and novel details in 60 the construction and operation of the device will be more particularly pointed out in the description to follow which for a clear understanding of the invention should be considered in connection with the accompanying drawings, forming a part hereof and wherein is disclosed for the purpose of illustration convenient and preferred embodiments of the invention.

In the drawings: Figure 1 is an elevation 70 of one form of sticker, Fig. 2 a cross section of same, Figs. 3, 4 and 5 show the application of the sticker, Figs. 6 and 7 are sectional views of a modified form of sticker, and Figs. 8 and 9 show applications of the 75

Again referring to the drawings wherein like reference numerals refer to corresponding parts throughout the several views and with more particular reference to Figs. 1 80 and 2, 1 is a body part of yieldable material, and preferably constructed of rubber. The said body part constitutes a connecting web between two preferably similarly constructed cup shaped members 2, which said cup 85 shaped members are preferably integral with said body portion and are offset laterally therefrom so as to present open spaces 3 extending substantially parallel with the longitudinal axis of the body portion. The 90 cup shaped members 2 are preferably formed of highly yieldable material preferably rubber or rubber composition and are adapted upon pressure being applied to the body portion overlying said cup shaped 95 members to be compressed thereby emitting the inclosed air and upon pressure being relieved to be retained in place by the created vacuum.

The sticker described presents practically 100 a continuous surface which will be pleasing to the eye and at the same time the cup shaped members 2 are substantially reinforced by the connected body portion which it will be noted overlies the base of the cup 105 shaped members thereby increasing the efficiency and durability of the device. It is preferred to employ a metallic reinforcing member 4 of any desired construction for the connecting web or body portion the same 110 being embedded in the rubber and preferably of spring sheet metal.

In Fig. 3 of the drawings it will be observed that the device is applied to a poster or card one cup shaped member overlying the card and the other being in direct engagement with the window pane or part to which the member is adapted to be applied. In Fig. 4 it will be seen that both cup shaped members engage directly the window pane or the like whereas the unobstructed space between the members, and the main portion of the body part 1 overlies the corners of the card or the like. In this connection the device is of especial advantage in use in retaining a card of heavy material, because of the substantial unobstructed space between the cup shaped members. Also various articles other than cards or the like may be supported in the same manner as illustrated in Fig. 5.

Various modifications are within the contemplation of the invention one of such being illustrated in Figs. 6 and 7, 8 and 9 in which 1 represents a body portion of yieldable material and preferably rubber the same having enlarged terminals 2 extending in the same general direction as the body portion and said terminals being recessed at 3 to constitute the vacuum cups. In this form of the invention, in use the body portion may be bent to the form illustrated in Fig. 7 and operates in substantially the same manner as the device heretofore described. This particular form of construction is also of especial advantage when it is desired to fit the device over corners of the window pane that is one terminal engaging one pane and the other another pane extending at angles to the first mentioned pane, when the same may constitute a clip

for receiving articles positioned in corners 40 of the window as illustrated in Fig. 8 or to engage a card or the like one on each pane as illustrated in Fig. 9.

What I claim as new is:

1. A vacuum sticker comprising spaced 45 rubber vacuum cups arranged to engage a surface and be retained in position by vacuum, and a member connecting said cups comprising an elongated integral extension of said cups, and said member being relatively thin and yieldable, whereby the cups may be positioned out of alignment to engage different surfaces, substantially as and for the purpose described. 50

2. An integral rubber structure for the 55 described purpose comprising an elongated body terminating at opposite ends in enlarged portions projecting at substantially right angles to the body portion and recessed to form vacuum cups, the space to 60 the side of the body portion and between the enlarged portions being unobstructed and forming a receiving pocket substantially as and for the purpose described.

3. An integral rubber structure comprising 65 a relatively thin elongated bendable body portion terminating at opposite ends in enlarged portions recessed to form vacuum cups, operating in the manner and for the purpose described, and a metal member embedded in the bendable part of said structure. 70

In testimony whereof I affix my signature in presence of two witnesses.

JAMES P. EVERETTS.
